CLAIM

The ornamental design for a tire for a bicycle, as shown and described.

DESCRIPTION

FIG. 1 is a side elevational view of a tire for a bicycle showing my new design, it being understood that the opposite side is a mirror image thereof;

FIG. 2 is an end elevation view thereof, it being understood that the tread pattern is repeated uniformly throughout the circumference of the tire;

FIG. 3 is an enlarged fragmentary perspective view thereof showing the tread pattern in greater detail; and,

FIG. 4 is a greatly enlarged cross-sectional view thereof taken along line 4—4 in FIG. 1.

FIG. 2

FIG. 1

FIG. 4

FIG. 3
